UNITED STATES PATENT OFFICE.

MAX FIX, OF NEW YORK, N. Y.

DESIGN FOR A PILLOW-SLIP.

50,836.

Specification for Design.

Patented May 29, 1917.

Application filed February 28, 1917. Serial No. 151,593. Term of patent 3½ years.

To all whom it may concern:

Be it known that I, MAX FIX, a citizen of the United States, residing at New York city, in the county of New York and State of New York, have invented a new, original, and ornamental Design for a Pillow-Slip, of which the following is a specification, reference being had to the accompanying drawing, forming part thereof.

The figure is a plan view of a pillow slip showing my new design.

Referring to the drawing, particularly to the features which are most prominent, the design consists of a pillow slip having a

rectangular body 10, from the side edges of which 11 and 12 extend inwardly the tapering flaps 13 and 14. The apices 15 and 16 of the flaps are spaced from each other to leave room for a suitable embroidered surface ornamentation 17 over which an embroidered character 18 is disposed.

I claim:

The ornamental design for a pillow slip, as shown and described.

MAX FIX.

Witnessed by—

M. S. MILLER,
NATHAN COHEN.
